TUBULAR CLOTH CASING

Edward F. McGighe, New York, N. Y.

Application September 30, 1950, Serial No. 187,811

2 Claims. (Cl. 2-255)

1

This invention relates to novel means for attaching stays or reenforcing strips to cloth; and more particularly to a covering for a stay, attached to a garment so as to hold the stay or strip flat against the cloth in correct position and prevent the stay from tearing or ripping the cloth.

An important object is to provide a strong and durable covering that will enclose a stay snugly and smoothly and can easily be fastened in place on the cloth without materially increasing the thickness thereof or of the garment fashioned therefrom. As a result superior neatness without loss or diminution of flexibility or reenforcing effect is attained.

The invention is clearly described in the following specification and illustrated on the accompanying drawings. But this disclosure is explanatory only, and I may adopt variations in details not shown herein, without altering or omitting any of the essential characteristics.

On the drawings

Figure 1 is a plan view of a piece of cloth having stays affixed thereto in accordance with my invention;

Figure 2 is a front view of the covering and the stay therein;

Figure 3 is a rear view of said covering with the stay fitted therein;

Figure 4 is a cross section of said covering on line 4-4 of Figure 3; and

Figure 5 is a similar section of the covering with the stay omitted.

A piece of cloth is indicated at 1 with stays or reenforcing strips 2 therein for parts of a garment, in which such an effect is needed. The stays are usually strips of flexible metal or other material and they may be coated with enamel or any other suitable substance.

The stays are slipped into flattened tubular coverings or casings 3 each of which is preferably made from textile material and in one piece without a seam. A casing made of a strip folded along its length and with the opposite longitudinal edges stitched together would have at least one extra layer along the seam of the casing where the edges thereof overlap. Hence the casing 3 or the cloth 1 or both would tend to become thicker and the cloth combined with the stay would be somewhat less pliant; and it is of course desirable to avoid any thickening of the cloth where the stays are attached, as much as possible. The tubular casing 3 without a seam and having only a single layer of relatively little thickness around the stay 2 gives this result to a marked degree.

2

Stays with strips of material glued to them have been tried for reenforcing cloth, but this mode of connecting stays to cloth tends to make the stay less pliant and less resiliant.

The tubular casing has integral flanges or elongated lateral extensions 4 along each side, and the stay 2 within the casing lies between the flanges.

The tubular casing 3 with the stay 2 in it is laid upon the cloth 1 and held by stitches 5 passing through the flanges 4 and the cloth 1 along the opposite side edges of the stay 2 therein. The interior of the flattened tubular casings has a little greater width than the stay, so that there are narrow spaces in the casing along the edges of the stay 2. These long narrow spaces permit the stays to move laterally edgewise to a small extent, but not enough for any of the stay to rotate in its casing 3 and present itself edgewise to the cloth 1. The stays are prevented from sticking out of the casings 3 at their end by stitches 6 across the ends thereof and through the cloth 1 but not too close to the ends of the stays 2. The inside spaces along the edges of each stay allow slight lateral movement of the stay, because if the stitches 5 were too close to the edges of the strips the latter are apt to tear or rip the cloth 1 or the tubular casing 3 at the ends; and this must of course be avoided. The stays are thus allowed a little free movement lengthwise and crosswise in the casings 3.

The cloth casing 3 has a central part 7 which has the form of sleeve or tube that receives the strip 2. The flanges 4 along the sides of the sleeve 7 are in one relatively thin layer and the sleeve 7 has a flat back layer and a flat front layer joined together at the edges and to the flanges 4 at each side. The back layer of the sleeve 7 is of the same weave or texture as the flanges 4, and so is the front or outer layer between the flanges 4. Along each side of the sleeve 7 is a binder thread 8 at the junction of the front layer and the back layer with the flanges 4. The front layer of the sleeve 7 is indicated at 9; its width is no more than the distance between the stitching flanges 4 and the back layer is indicated at 10. The binder thread 8, shown exaggerated in Figure 3, is invisible when the whole covering is finished, but gives the sleeve 7 well defined edges along the sides where the front layer 9 merges with the side flanges 4. The binder thread 8 is worked in when the sleeve with the side flanges is woven.

A tubular casing of this kind having a sleeve 7, flanges 2, and binder threads 8, with a stay therein, attached to the cloth 1 wherever a rein-

forcing is required, by stitches going through both flanges 4 and the cloth but leaving a little free space in the sleeve 7 at the ends and along the sides of each stay 2 gains all the objects of this invention. And while the casings 3 are described as consisting of textile fibres worked in such a way as to produce the cloth, other material for the tubular casings 3 may also be employed, so long as the casings are one piece without seam. The cloth 1 is thus reenforced by the stays 2 as much as necessary, but it remains flexible and the garment made from such cloth lasts longer and gives the maximum degree of comfort to the wearer.

The width of the long narrow spaces in the tubes 7 may be as small as .001 of an inch at each side of the stay; and the spaces between the ends of the stays and the stitches 6 need not be over sixteenth of an inch. The layers 9 and 10 are thus relieved of stresses to such an extent that the ends of the stays cannot tear the stitches 5 or 6 or the casing adjacent these stitches.

The binder threads 8 joining at the junction of the front layer 9 of the sleeve 7 to the back layer 10 and to the flanges or extensions 4 give a beaded effect to the sleeve along the front layer 9 or outer face of the covering and increases the neat effect of the finished casing and side flanges 4. The binder threads are worked in when the casing is woven and they are useful both to keep the article straight while it is being formed in the loom; and in use such threads add some stiffness to the casing so that the stays can be more easily inserted. The binder threads tend to keep the casing straight and smooth when the stay is inserted there is less risk of the end of the stay catching against the inside of the sleeve and bending or producing a tear in the threads of the article.

The binder threads assure constant width of the sleeve 7 and flanges 4 within the loom during

the weaving operation, and greatly strengthen the product when it leaves the loom in finished form and is ready for use.

Having described my invention, what I believe to be new is:

1. Cloth having a stay in the form of a long flat strip secured thereto, said stay being enclosed in an elongated tubular casing having a flattened longitudinally extending central sleeve with elongated lateral extensions of relatively little thickness united to the sleeve, one along each side of said sleeve, said casing being affixed to the cloth by stitches along said extensions adjacent said stay therein, said sleeve around the stay on both faces of the casing being of substantially the same thickness as the extensions, said casing having a binder thread at the junction of at least one extension with the sleeve, the stitches passing through the extensions into the cloth, said casing being also stitched to the cloth adjacent the ends of the stay and at points spaced from said end but near thereto, said sleeve being only slightly wider than said stay.

2. A flat tubular elongated casing of textile material having a central longitudinal sleeve and a flange at each side united to the sleeve for stitching the casing to cloth, the sleeve being adapted to envelop a stay to reinforce the cloth, the sleeve and flanges being of the same thickness, and a binder thread along a junction of at least one of said flanges with the sleeve.

EDWARD F. MCTIGHE.
